UNITED STATES PATENT OFFICE

2,325,642

MACHINE FOR ACTING ON CARTRIDGE CASES

Joseph E. Turnock, Riverton, N. J., and Gerard D. Noble, Philadelphia, Pa.

Application March 27, 1940, Serial No. 326,208

1 Claim. (Cl. 86—23)

(Granted under the act of March 3, 1883, as amended April 30, 1928; 370 O. G. 757)

The invention described herein may be manufactured and used by or for the Government for governmental purposes, without the payment to us of any royalty thereon.

This invention relates to a machine for acting on cartridge case.

The purpose of the invention is to provide a machine which will burr a cartridge case, detect for the absence of a case, form a vent, detect for the absence of a vent, insert a primer, detect for an inverted primer or the absence of a primer, seat and crimp the primer, apply a waterproofing material and wipe excess material from the primer.

The machine is characterized by an organization of driving mechanism which is beneath the bed over which the cartridge cases are transferred to prevent oil or other foreign matter from dropping on or into the cases or primers as they are being transferred from station to station.

The machine also includes novel mechanism for supplying cartridge cases and for moving them from station to station, for stopping the machine in response to the detect elements, and for feeding primers to the case.

The specific nature of the invention as well as other objects and advantages thereof will clearly appear from a description of a preferred embodiment as shown in the accompanying drawings in which:

Fig. 1 is a view in front elevation of the machine;

Fig. 2 is a plan view;

Fig. 3 is a sectional view on the line 3—3 of Fig. 1, parts omitted;

Fig. 4 is a sectional view on the line 4—4 of Fig. 1;

Fig. 5 is a view in right side elevation;

Fig. 6 is a view in left side elevation;

Figs. 7 to 10 are sectional views on the corresponding lines of Fig. 1;

Fig. 11 is a plan view of the transfer mechanism;

Fig. 12 is a view in front elevation thereof;

Fig. 13 is a view on the line 13—13 of Fig. 7;

Fig. 14 is a similar view with the transfer bar in a different position;

Fig. 15 is a sectional view on the line 15—15 of Fig. 13;

Fig. 16 is a perspective view of an element of the transfer mechanism;

Fig. 17 is an enlarged sectional view on the line 17—17 of Fig. 7;

Fig. 18 is a view in elevation of an element of Fig. 17;

Fig. 19 is a plan view of the primer inverter;

Fig. 20 is a view in elevation of Fig. 19 with parts in section;

Fig. 21 is an exploded view of elements of the throw-out mechanism;

Fig. 22 is a sectional view on the line 22—22 of Fig. 24;

Fig. 23 is a sectional view on the line 23—23 of Fig. 22;

Fig. 24 is a plan view partly in section of the varnishing mechanism;

Fig. 25 is a sectional view on the line 25—25 of Fig. 24;

Fig. 26 is a sectional view on the line 26—26 of Fig. 25;

Fig. 27 is a sectional view on the line 27—27 of Fig. 5;

Fig. 28 is a sectional view on the line 28—28 of Fig. 27;

Fig. 29 is a sectional view of the base of a cartridge case loaded with a primer.

The machine comprises a support consisting of a lower plate 5, upright posts 6 and an upper plate 7. Guides 8 on the lower plate (Fig. 6)

25 support four vertical rods 9 which pass through the upper plate 7 and carry an upper crosshead 10 at their upper extremities. A lower crosshead 11 is slidably mounted on the rods 9 below the upper bed plate 7 (Figs. 9 and 10). Each pair of

30 rods 9 at the sides of the machine are connected by a bearing member 12 which is fitted to the rods, and the pair of bearing members carry a shaft 13. A pair of connecting rods 14—14 on the shaft 13 are associated with conventional

35 eccentrics (not shown) on a drive shaft 15. A pair of connecting rods 16—16 on the lower crosshead 11 are similarly associated with eccentrics (not shown) on the drive shaft. The eccentrics are oppositely arranged as indicated in Fig. 1 so that the upper and lower crossheads are simultaneously moved towards and from the upper plate 7.

The lower crosshead carries on its upper side seven stems 17 which are adapted to enter the mouth of a cartridge case A and which are arranged in line in spaced relation. The upper crosshead carries seven tools which are designated as subs of 18 which are adapted to engage the base of the cartridge and which are in alignment with the stems 17. The cartridge case A (Fig. 29) has a preformed cavity a when it is introduced into the machine. The cartridge case after passing through seven stations represented by the seven tools is shown in Fig. 29. The operations to be performed at the seven stations are

45

40

45

50

55

as follows—No. 1, burring and detecting the absence of a cartridge case; No. 2, venting; Nos. 3 and 4, detecting the absence of the vent; No. 5, inserting a primer; No. 6, detecting the absence of a primer or an inverted primer; No. 7, seating 5 and crimping the primer.

The cartridge cases are fed from a hopper B and pass by gravity base end foremost down an inclined chute or tube 19 which terminates in a vertical magazine 20 (Figs. 7 and 17) fixed to 10 the upper plate 7. The upper end of the magazine has a large mouth and at one side there is an inclined trough 21 which is in continuation of the tube so that a cartridge case may slide down the trough until brought to rest by the 15 inclined plate 22.

A rocker 23 pivotally carried by the magazine is engageable by a cam 24 on the upper crosshead so that upon reciprocation of the latter the rocker will be intermittently moved to insert a pair 20 of fingers 25—25 (Fig. 18) into the magazine and push the cartridge out of the trough. As the case rolls from the trough the base is positioned in rear of and above a pin 26 so that the front 25 of the case will fall first, thereby being inverted and emerging mouth foremost from the magazine. The magazine includes a hinged portion 20a and a plunger 20b for clearing jams. The case now drops alongside a rail 27. (Figs. 7 and 8), its upper portion disposed in the slot of an upper guide plate 28 mounted above the rail 27 and its lower shoulder portion being disposed in a slot in a lower guide plate 29 mounted below the rail 27. The lower edge of the case rests on a bar 30 (Fig. 7) which has apertures 31 (Fig. 8) through which the stems 17 pass to enter the case. As seen in Figs. 13 and 17 an end block 32 is provided to support one side of the intermediate portion of the case as it arrives from the magazine. The opposite side of the case is engaged by the recessed end of a pivoted holding finger 33 whose movement under the action of a spring 34 is limited by the engagement of a nose 35 with a block 36. A plurality of fingers are provided to correspond to step by step movement of the cartridge case across the machine.

The means for imparting a step by step movement to the cartridge cases comprises a transfer bar 37 (Figs. 13 and 14) having a plurality of sets of vertically spaced and aligned recesses 38 and 39 adapted to partially embrace a cartridge case. The transfer bar has a quadrangular motion, advancing from an initial retracted position as in Fig. 13 to the cartridge engaging position of Fig. 14, then feeding one step to the left, retracting, and finally returning to initial position.

The mechanism for performing this operation comprises a pair of slides 40—40 (Fig. 16) mounted in the upper plate 7 (Fig. 15). A block 41 fixed to the inner end of each slide is provided with a pair of bolts 42—42, each carrying a roller 43 disposed in a slot 44 in the transfer bar. Each block is connected by means of a pair of spaced links 45—45 to a lever 46 keyed on a shaft 47 which is journaled in brackets 48. A guide plug 49 on the outer end of each block slides in a tubular housing 50 (Fig. 15) fixed to the plate 7 and acts on helical spring 51 which is seated on the outer plug 52 in the housing (Fig. 7) and serves to advance the transfer bar.

The shaft 47 is rocked by means of a link 53 (Figs. 5 and 6) which connects a lever 54 on the shaft and an angled lever 55 pivotally mount-

ed in a hanger 56 attached to a bracket 57. The free end of the lever 55 rides on a cam 58 on the drive shaft. This mechanism serves to retract the transfer bar against the action of springs 51. A lever 59 pivotally mounted in a bearing 60 carried by bracket 57 has its upper end pivotally attached to a coupling 61 (Fig. 11) on the transfer bar and its lower end provided with a cam pin 62 riding in a cam slot 63 on the drive shaft. This mechanism serves to reciprocate the transfer bar.

Referring to Fig. 1 the tools 18a, 18c—18d, and 18f, which are employed at "detect" stations, are associated with mechanism for automatically stopping the machine. As seen in Fig. 2 there are three horizontal shafts 64 journaled on the upper side of the upper crosshead. Similar levers 65 fixed on the end shafts engage the tools 18a and 18f while a single lever 66 engages both tools 18c and 18d. Each shaft carries a depending finger 67 (Fig. 8) which is adapted on lowering of the crosshead to strike the horizontal arm of a bell crank lever 68 (Fig. 1) pivotally carried by a vertical plate 69 (Fig. 8) fixed to the plate 7. The slotted lower end of the vertical arm of lever 68 engages a pin 70 on a horizontal latch bar 71 (Fig. 21). The latch bar is normally held by a spring 72 at its left end into the path of a lug 73 on the upper end of a vertically slideable bar 74 whose movement is limited by spaced stop pins 75—75 adapted to engage opposite sides of a guide member 76.

The vertical bar 74 is provided with another lug 77 for supporting a pivoted throw-out lever 78 (Fig. 5). A link 79 normally depressed by a spring 80 connects the lever 78 with a plate 81 slidably mounted in a guide 82. The plate 81 has an arcuate lower end formed with a cam surface 83 (Fig. 28) adapted to enter a peripheral groove 84 in a collar 85 keyed to the drive shaft. A key 86 slidably mounted in the collar 85 is normally urged by a spring 87 into a recess 88 in a gear wheel 89 which is driven from a source of power indicated by gear wheel 90. The key is formed with a slot 91 to provide a cam follower 92 which is normally disposed in the groove 84 in the collar 85. When the plate 81 is lowered into the groove 84 of the rotating collar 85 the cam follower which is rotating with the collar will engage the cam 83 and the key will be declutched from the gear wheel 89.

A metal sleeve 93 shrunk on the collar 85 rides within a pair of brake shoes 94 (Fig. 5) which are pivotally mounted on the support and urged together by a spring 95.

Referring to Fig. 2 primers which are to be placed in the cartridge case are hand-fed, anvil side up, onto a rotating tray 96 which is mounted on a spindle 97 (Fig. 8) driven by gearing 98 from a shaft 99 (Fig. 1) pulley 100 and belt 101 which is associated with the drive shaft. A plate 102 (Fig. 2) supported by the spindle (Fig. 8) is fixed to an arm 103 forming part of a flange 104 secured to plate 7. The arm is additionally supported by a bracket 105. The arm is spaced from the plate 102 to provide a channel 106 for the passage of the primers in single file. The plate 102 cooperates with the flange 104 and the base of the arm 103 to provide a converging path for the primers on the tray. At the mouth of the channel 106 the plate carries an agitator comprising a slide 107 moved by one arm of a lever 108. The other arm of the lever engages an annular row of pins 109 on a disk 110 which is fixed to the spindle. The lever is rocked in

one direction by the pins 109 and it is returned by a spring 111.

At the exit of the channel the foremost primer is brought up against a stop plate 112. A feed finger 113 reciprocable between the stop plate 112 and the plate 102 (Fig. 2) is actuated by a lever 114 (Fig. 9), which is pivoted on a hanger 115 attached to the plate 7. The lever 114 carries a roller 116 which rides on a cam 117 forming part of a rack bar 118 secured to the lower crosshead 11. The roller is held against the cam by a spring 119.

Referring to Figs. 19 and 20 the finger 113 pushes the primer between the spring held jaws of a clamp 120 which is carried by a shaft 121 mounted on pins 122 in a bracket 123. A pinion 124 on the shaft meshes with the teeth on rack bar 118 (Figs. 9 and 10), so that the shaft is rocked through an angle of 180 degrees on reciprocation of the lower crosshead 11. The clamp 120 carried by the shaft moves through a corresponding angle to reverse the primer and position it, anvil side down, above the cavity *a* of the cartridge case A so that the tool 18e at station No. 5 may push it out of the clamp and insert it into the cavity *a*.

Tool 18a is provided with an adjusting collar 125 and a spring 126. Tools 18b, 18e, and 18g are fixed while tools 18c, 18d, and 18f are similarly provided with a spring 127. Similar strippers 128 (Fig. 3) for engaging and holding the cartridge case are provided for the stations of tools 18b, c, and d and a different type of stripper 129 is provided for the station of tool 18g.

The upper plate 7 extends at one side of the machine to carry a varnishing and waterproofing mechanism which comprises a pair of reservoirs 130 and 131 (Figs. 6 and 24), the reservoir 130 adapted to supply varnish or a waterproofing material through a valved pipe 132 to a lower tank 133 (Fig. 25) below the plate 7 and the reservoir 131 adapted to supply varnish through a valved pipe 134 and trough 135 (Fig. 24) to an upper tank 136 above the plate 7. An applicator 137 (Fig. 25) disposed in the lower tank 133 is carried by a bent rod 138 which extends out of the tank and is fixed to a vertically slidable bar 140. The applicator 137 is adapted to enter the mouth of the cartridge case and coat the inside wall evenly with varnish.

The upper tank 136 is disposed at one side of the cartridge which at this stage in its travel is raised above the guide plate and is supported by spaced rails 141-141 (Figs. 22 and 25) which engage the rim of the cartridge case. An applicator 142 associated with the upper tank is carried by a vertically movable slide 143 which in turn is carried by a horizontally movable slide 144 mounted in a guide 145. A roller 146 on the vertical slide is arranged to engage a transversely disposed arcuate cam 147 fixed to a bracket 148 and it is held against the cam by means of a compression spring 149 whose lower end is connected to a spring seat 150 carried by the horizontal slide 144.

The slide 144 is formed with a tubular bearing 151 which slidably receives an end of a rod 152 which is pivotally connected to one arm of a bell crank lever 153. A helical spring 154 embracing the rod is confined between the bearing 151 and 70

the outer pivoted end of the rod. The end of the rod which projects through the bearing carries a collar 155 for engaging the bearing and it also carries a set screw 156 for engaging the lower arm 157 of a bell crank lever. The upper arm 158 of this lever is adapted to strike the vertical slide 143 to move the applicator towards the cartridge case where it deposits a drop of varnish on the primer. The slide 144 is moved to the right in Fig. 25 through the intermediation of the spring 154 and it is stopped in predetermined position by a set screw 159 while the rod continues its movement to strike the arm 157. Movement of the slide to the left is accomplished by engagement of the collar 155 with the bearing 151.

The actuating mechanism for the elements carrying the applicators comprises a connecting rod 160 (Figs. 6 and 25) which is reciprocated by the drive shaft and is connected to the lower arm of bell crank lever 153 pivoted on bracket 148. The connecting rod is also connected by means of a link 161 to a lever 162 which is pivotally mounted on the lower part of the bracket 148 and has a link 163 connected to the vertically slidable bar 140.

Referring to Fig. 6 there is shown an endless belt 164 trained around spaced lower pulleys 165-165 and a single upper pulley 166 which is slidably mounted on a vertical rod 167 and normally elevated by a spring 168. A ratchet wheel 169 associated with one of the pulleys is intermittently driven by a pawl 170 carried by lever 171. The lever 171 is actuated by link 172 from 35 the connecting rod 160.

An arm 173 pivotally mounted on the bracket 148 carries a roller 174 which engages the inner reach of the belt above the cartridge case. A link 175 connects the arm with lever 162 and 40 serves to intermittently depress the arm so that the roller will move the belt into contact with the base of the cartridge case in order to wipe excess varnish from the primer.

Referring to Fig. 22 when the cartridge case reaches the end of its travel by the action of the transfer bar 31a member 176 on the end of the bar pushes the case onto a drying rack 177.

The operation has been described in connection with the description of the component elements.

We claim:

In a machine of the character described, a bed plate, means for supplying cartridge cases to the bed plate, open end down, means for moving the cases step by step across the plate, an elongated perforated plate engaged by the open ends of the cases in their lineal movement across the bed plate, jointly reciprocable tools above the bed plate for acting on the bases of the cases and longitudinally arranged with respect to the path of movement of said cases, jointly reciprocable stems below the bed plate and positioned to extend through the perforations in the elongated plate and into the cases to assist in locking them in true vertical position and means for simultaneously reciprocating the tools and stems in opposite directions.

JOSEPH E. TURNOCK.
GERARD D. NOBLE.
